UNITED STATES PATENT OFFICE.

HARRY RALPH RICARDO, OF LONDON, ENGLAND.

HYDROCARBON ENGINE.

1,425,054.

Specification of Letters Patent. Patented Aug. 8, 1922.

Application filed September 28, 1920. Serial No. 413,257.

To all whom it may concern:

Be it known that I, HARRY RALPH RICARDO, subject of the King of England, residing at London, in England, have invented 5 certain new and useful Improvements in Hydrocarbon Engines, of which the following is a specification.

The present invention relates to improvements in hydrocarbon engines and particularly to means for cooling and lubricating 10 the pistons and cylinder walls. Other advantages of the invention will appear from the following specification taken in conjunction with the accompanying drawing.

15 The drawing shows in cross section, more or less diagrammatically, the application of the present invention to a piston of the type illustrated in applicant's Patent No. 1,346,845, dated July 20, 1920.

20 Referring to the drawing 10 indicates the cylinder of a hydrocarbon engine, 11 the combustion chamber, 12 the inlet and exhaust valves and 13 the crank case.

25 The piston 14 is of the "cross head" type having a rearwardly extending trunk or tubular stem 15 in which a gudgeon pin 16 is mounted. The gudgeon pin may be mounted in the tubular stem and the connecting rod 17 connected to the gudgeon 30 pin as shown in the patent mentioned.

Between the cylinder and the crank case there is a transverse passage 18 the walls of 35 which are preferably cast integral with the crank case as shown. The passage 18 is separated from the crank case by a wall 19 and has an upper wall 20 on which the cylinder is mounted.

40 The cross head guide cylinder 21 is supported by a flange 22 which, as shown, is clamped between the cylinder 10 and the wall 20, the lower end of the cross head guide cylinder communicating with the crank case through its open end 23 which is fitted tightly in the upper wall 19 of the 45 crank case. The transverse passage 18 is in communication with the interior of the cylinder below the piston through a series of passages 24 between the guide cylinder wall and the flange 22. The tubular piston stem 50 15 is surrounded by a sleeve 25 which is spaced from the tubular stem and rigidly connected therewith and which fits closely in the cross head guide cylinder. The sleeve 25 extends above and below the 55 gudgeon pin and takes practically all of the lateral thrust and wear due to the re-

ciprocation of the piston. The sleeve may be connected to the piston stem in any desired manner and, as shown, is connected in the manner described in the aforesaid Patent No. 1,346,845. Openings 26 in the piston stem and openings 27 in the sleeve 25 permit of the passage of air and oil for lubricating the cross head and also for lubricating the piston and cylinder, as will be presently described.

The operation of the described mechanism is as follows: The air for cooling purposes is circulated through the transverse passage 18 around the guide cylinder 21, as indicated by the arrows. The guide cylinder is preferably provided with ribs 21^a which facilitate radiation of heat which is carried off by the air. The air may be circulated by any suitable means as by connecting the outlet of the channel 18 with the air intake of the carburetor. As the piston 14 moves outward or, as shown, in an upward direction, air is drawn from the passage 18 through the somewhat restricted openings 24, into the cylinder below the piston. The air is forced out again as the piston descends and passes on to the carburetor or escapes, and this circulation of air assists in cooling both the piston and cylinder.

It is well known that the oil in the crank case of a rapidly moving hydrocarbon engine is broken up and distributed so that it is largely in the form of a cloud or fog which fills the crank case and lubricates all parts to which the cloud or fog of oil has access. In the present case oil in the form of vapor will exist in the cross head guide cylinder 21 and in the tubular piston stem 15 and owing to the suction created by the upward movement of the piston this vapor will be drawn through the openings 26 and 27 as soon as the openings 27 pass above the upper end of the cross head guide cylinder 21. In the drawing the uppermost position of the piston and its attached parts is shown in dotted lines and as the piston approaches this position the oil vapor will be drawn through the openings 26 and 27 and projected on the cylinder wall, as indicated by the broken arrows 30. Sufficient vapor will thus be projected into the cylinder to keep the cylinder and piston properly lubricated.

The amount of oil supplied to the piston and cylinder will depend more or less upon the speed of the engine, more being sup-

plied at high speeds, but the manner in which the oil is supplied practically prevents over lubrication. It is well known that a portion of the piston lubricating oil becomes carbonized and some of the carbonized oil is scraped from the cylinder by the piston rings and, in ordinary engines, is returned to the crank case, thus injuriously affecting the lubricating qualities of the main oil supply. In the present case the oil which is supplied to the cylinder walls does not return directly to the crank case but runs into the transverse channel 18 from which it may be drained and filtered before returning to the crank case thus prolonging the useful life of the oil in the crank case and preventing wear upon the moving parts by eliminating more or less gritty carbon which is formed in the cylinders.

It will be obvious from the foregoing description that by means of the present invention the cylinder and piston of the engine is more effectually cooled and lubricated than in hydrocarbon engines as heretofore constructed and also that the oil in the oiling system is maintained in a purer condition. An advantage may also be obtained by directing the warm cooling air to the carburetor to assist in vaporizing the fuel.

What I claim as my invention and desire to secure by Letters Patent is:—

1. In a hydrocarbon engine the combination with the crank case, the cylinder and a piston having an elongated stem and a cross-head, of a tubular crosshead guide having one end in communication with the crank case and the other end in communication with the cylinder and means for circulating air around substantially the entire outer surface of said crosshead guide for cooling purposes.

2. In a hydrocarbon engine the combination with the crank case, the cylinder and a piston having an elongated stem and a crosshead, of a tubular crosshead guide having one end in communication with the crank case and the other end in communication with the cylinder, and means for circulating air about substantially the entire outer surface of said guides and into and out of the cylinder, for the purpose set forth.

3. In a hydrocarbon engine the combination with the crank case, the cylinder and a piston having an elongated stem and a crosshead, of a tubular crosshead guide having one end in communication with the crank case and the other end in communication with the cylinder, a transverse air passage above the crank case and in which said crosshead guide is located, said air passage extending substantially around the en-

tire outer surface of the guide, and means for circulating air through said passage.

4. In a hydrocarbon engine the combination with the crank case, the cylinder and a piston having an elongated stem and a crosshead, of a tubular crosshead guide having one end in communication with the crank case and the other end in communication with the cylinder, a transverse air passage above the crank case and in which said crosshead guide is located, and means for circulating air through said passage, said passage being in communication with the cylinder whereby air is drawn into the cylinder at each outward stroke of the piston, for the purpose set forth.

5. In a hydrocarbon engine the combination with the crank case, the cylinder, and a piston having an elongated stem and a crosshead of a tubular crosshead guide of less diameter than the cylinder and communicating with the cylinder and crank case, the said crosshead having radial openings through which oil vapor is drawn and projected on the cylinder during the upward stroke of the piston.

6. In a hydrocarbon engine the combination with the crank case, the cylinder, and a piston having an elongated stem and a crosshead of a tubular crosshead guide of less diameter than the cylinder and communicating with the cylinder and crank case, the said crosshead having radial openings through which oil vapor is drawn and projected on the cylinder during the upward stroke of the piston and means for preventing excess oil in the cylinder from draining into the crank case, for the purpose set forth.

7. In a hydrocarbon engine the combination with the crank case, the cylinder, and a piston having an elongated stem and a crosshead of a transverse air passage above the crank case, said air passage having an upper wall supporting the cylinder and a tubular crosshead guide having a flange intermediate said upper wall and cylinder whereby said crosshead guide is supported.

8. In a hydrocarbon engine the combination with a crank case, a cylinder, and a transverse air passage having upper and lower walls, said lower wall forming a partition between the air passage and the crank case and said upper wall supporting the cylinder, a piston in said cylinder having an elongated stem and a crosshead and a tubular crosshead guide arranged transversely of the air passage and having one end opening into the crank case and its other end opening into the cylinder.

9. In a hydrocarbon engine the combination with a crank case, a cylinder, and a transverse air passage having upper and lower walls, said lower wall forming a par-

tition between the air passage and the crank case and said upper wall supporting the cylinder, a piston in said cylinder having an elongated stem and a crosshead and a 5 tubular crosshead guide arranged transversely of the air passage and having one end opening into the crank case and its other end opening into the cylinder, said crosshead guide being smaller than the cylinder and permitting air to circulate between the guide and cylinder, for the purpose set forth.

10. In a hydrocarbon engine the combination with a crank case, a cylinder, and a 15 transverse air passage having upper and lower walls, said lower wall forming a partition between the air passage and the crank case and said upper wall supporting the

cylinder, a piston in said cylinder having an elongated stem and a crosshead and a 20 tubular crosshead guide arranged transversely of the air passage and having one end opening into the crank case and its other end opening into the cylinder, said 25 crosshead guide being smaller than the cylinder and permitting air to circulate between the guide and cylinder, and the stem of the piston being hollow and provided with openings whereby the oil from the crank case may be drawn through the piston stem and projected upon the cylinder during the upward movement of the piston, for the purpose set forth.

In testimony whereof I have signed by name to this specification.

HARRY RALPH RICARDO.
